UNITED STATES PATENT OFFICE

ALFRED F. TEITSCHIED, OF WHARTON, NEW JERSEY

COMBINATION FUSE

Application filed June 27, 1928. Serial No. 288,570.

(GRANTED UNDER THE ACT OF MARCH 3, 1883, AS AMENDED APRIL 30, 1928; 370 O. G. 757)

The invention described herein, may be manufactured and used by or for the Government for governmental purposes, without the payment to me of any royalty thereon.

5 The subject of this invention is a combination fuse.

In combination fuses designed to be set either for super-quick or delay action, the structure of the fuse casing and the structure 10 which holds the impact striker of the super-quick mechanism in operative position must be strong enough to withstand the shock of impact for a sufficient length of time to permit functioning of the delay firing mechanism.

15 In designing a fuse which will meet this requirement and which may be easily constructed and readily assembled I have incorporated therewith a novel form of super-quick and mechanical delay firing mechanism elements of which are insertable as units in the fuse.

With the foregoing and other objects in view, my invention resides in the novel arrangement and combination of parts and in the details of construction hereinafter described and claimed, it being understood that changes in the precise embodiment of the invention herein disclosed may be made within 25 the scope of what is claimed without departing from the spirit of the invention.

A practical embodiment of the invention is illustrated in the accompanying drawing, wherein:

30 Fig. 1 is a longitudinal sectional view of the improved fuse shown in the normal unarmed position;

Fig. 2 is a similar view showing the delay firing mechanism in position of operation, and

Fig. 3 is a sectional view on the line 3—3 of Fig. 1.

Referring to the drawing by numerals of reference:

35 In carrying out the invention there is provided a container consisting of a hollow head 5 which is in threaded engagement with a body 6 formed with a cavity 7 in its forward portion. In the floor of the cavity is a disk 8 having a central aperture 9 and also an

annular recess 10 in its forward face for seating a carrier 11. The carrier is enlarged as at 12 intermediate its ends and threaded to the forward walls of the body 6, an arrangement which lends support to the body to 55 withstand deformation on ricochet impact. It is formed with a small bore 13 in which are placed nested thimbles 14 whose closed ends 15 are spaced from each other to provide a space for the detonator 16 and whose 60 open ends 17 are turned over to rest on the floor of a large bore 18. The thimbles are held in place by a guide plug 19 which is apertured to receive a firing pin 20.

The firing pin is formed with a collar 21 and has a stem 22 whose forward end 23 is semicylindrical and this semicylindrical end is provided with a notch 24 adapted to receive a complementary projection 25 on the semi-cylindrical portion of a dog 26. The dog is 70 pivoted by a pin 27 to a ring 28 adapted to seat on the forward face of an apertured disk 29 held in place against the carrier by the nose 30 of the fuse. A spring 31, confined between the collar 21 and the disk 29, urges 75 the firing pin towards the detonator but this action is restrained as long as the dog is held against pivotal movement by the disk 29. The firing pin is capable of being released from the dog when on impact of the fuse it is 80 moved forwardly by reason of its inertia to the position shown in Fig. 2. The spring in recovering forces the dog out of locking engagement and drives the firing pin home. This action will cause a delay firing of an 85 auto-selective character, especially suitable for obtaining an air burst when the projectile is ricocheted. The firing pin 20, dog 26, collar 27 and disk 29 are assembled as a unit 90 for insertion in the carrier.

The nose 30 of the fuse is insertable through an opening 32 in the fuse head and is threaded to the carrier. It is formed with a chamber 33 conformable to the large bore 18 in the carrier to allow for the forward movement of the firing pin unit. Mounted in the nose and having access to the chamber 33 is a striker 34 which when driven inwardly comes into contact with the dog shearing the pivot pin 27 and forcing the firing pin to 100

set off the detonator and produce a super-quick functioning of the fuse. The striker is held in place by a shear pin 35 and is further maintained in the safe position by half blocks 36 which are encircled by a weighted tape 37 centrifugally released during flight.

5 A cap 38 is threaded to the nose to retain the half blocks and it is removed only when the fuse is to be set for super-quick action.

10 The body 6 of the fuse is formed with an eccentric cavity 39 in which is pivoted a rotor 40 confined by the disk 8 and carrying a detonator 41. The rotor is maintained in the unarmed position with the detonator out of axial alinement by means of a pin 42 which functions on set-back to release the rotor which is then free to move to the armed position under the influence of centrifugal force. In the armed position the rotor bears tightly against 20 the wall of the cavity and is thereby restrained against counter movement due to force set up on impact. Because of the direct connection between the nose of the fuse and the disk 8 any pressure resulting from 25 impact will act to prevent counter movement of the rotor.

I claim:

1. In a fuse, a body formed with a cavity, a disk on the floor of the cavity, a hollow head 30 attached to the body, a detonator carrier attached intermediate its ends to the forward end of the body and resting on the disk, a nose insertable through the hollow head and attached to the carrier, a mechanical delay firing mechanism assembled as a unit and held in place by the adjoining ends of the nose and carrier, a striker carried by the nose in line with the delay firing mechanism, centrifugally releasable means for holding the striker 35 inoperative and a cap removably secured to the nose for holding said means in place.

2. In a fuse, a body formed with a cavity, a disk on the floor of the cavity, a hollow head attached to the body, a detonator carrier attached 40 intermediate its ends to the forward end of the body and resting on the disk, a nose insertable through the hollow head and attached to the carrier, a mechanical delay firing mechanism assembled as a unit and held in place by the adjoining ends of the nose and carrier and a striker carried by the nose in line with the delay firing mechanism.

3. In a fuse, a body, a hollow head attached to the body, a detonator carrier attached 45 intermediate its ends to the forward end of the body, a nose insertable through the hollow head and attached to the carrier, a mechanical delay firing mechanism assembled as a unit and held in place by the adjoining ends 50 of the nose and carrier, and a striker carried by the nose in line with the delay firing mechanism.

4. In a fuse, a body, a hollow head attached to the body, a detonator carrier attached 55 intermediate its ends to the forward end of

the body, a nose insertable through the hollow head and attached to the carrier, the carrier and nose formed to provide a chamber, a delay firing mechanism positioned in said chamber and an impact striker in the nose capable of actuating the delay firing mechanism.

5. In a fuse, a body, a hollow head attached to the body, a detonator carrier attached to the body, a nose insertable through the hollow head and attached to the carrier, the carrier and nose formed to provide a chamber, a delay firing mechanism positioned in said chamber and an impact striker in the nose capable of actuating the delay firing mechanism.

6. In a fuse, a two-part casing, an apertured disk held between the parts of the casing, a firing pin having a collar and a semi-cylindrical notched end portion insertable through the aperture in the disk, a dog having a semi-cylindrical end portion insertable through the aperture in the disk and engageable with the notched end of the firing pin, a ring in which the dog is pivoted, a spring confined between the collar of the firing pin and disk and a striker spaced from the dog and engageable with the dog on impact to break its pivotal connection on the ring.

7. In a fuse, a fixed apertured disk, a firing pin having a collar and a semi-cylindrical notched end portion insertable through the aperture in the disk, a dog having a semi-cylindrical end portion insertable through the aperture in the disk and engageable with the notched end of the firing pin, a ring in which the dog is pivoted, a spring confined between the collar of the firing pin and disk and a striker spaced from the dog and engageable with the dog on impact to break its pivotal connection to the ring.

8. In a fuse, a fixed apertured disk, a firing pin having a collar and a semi-cylindrical notched end portion insertable through the aperture in the disk, a dog having a semi-cylindrical end portion insertable through the aperture in the disk and engageable with the notched end of the firing pin, a ring in which the dog is pivoted, and a spring confined between the collar of the firing pin and disk.

9. In a fuse, a firing pin, a spring for actuating the pin and pivoted locking means axial with the pin normally holding the firing pin against the action of the spring and releasable upon movement of the firing pin under the influence of inertia.

10. In a fuse, a firing pin, a spring for actuating the pin and locking means carried by the firing pin normally holding the firing pin against the action of the spring and releasable upon movement of the firing pin under the influence of inertia.

ALFRED F. TEITSCHIED.
